UNITED STATES PATENT OFFICE

2,519,374

VIBRATOR

Ulysses S. James, deceased, late of West Orange, N. J., by Fannie B. James, executrix, West Orange, and Ulysses S. James, Jr., Livingston, N. J.; said Fannie B. James assignor to said Ulysses S. James, Jr.

Application June 10, 1946, Serial No. 675,564

12 Claims. (Cl. 74—26)

1

The present invention relates to a vibrator for reciprocating a surface to effect the advance of materials thereover, and it relates more specifically to vibrators for concentrating tables for effecting the wet separation of materials of different specific gravities, such as minerals from other constituents of ores.

In separating minerals from ores by the wet method, the ore is pulverized to a greater or lesser degree, depending upon the natural characteristics of the ore and of the mineral to be extracted. The pulverized ore is mixed with water and deposited upon a concentrating table where the heavier mineral portions settle to the bottom by gravity, and from which the settled particles are removed by a vibratory motion imparted to the table.

When the ore is reduced to a substantially impalpable powder, the mixture thereof is termed "slime"; whereas the coarser ground ore is termed "sand." In separating a mineral from "slime," a vibratory motion of a different characteristic is necessary, than that employed in separating a mineral from "sand": and in order to effect the highest percentage of recovery from the slimes, motions of different characteristics are necessary—depending upon the nature of the ore being treated.

One of the primary objects of the invention is to provide novel means for imparting to a concentrating table differential strokes having characteristics which enable low grade ores or slimes to be separated with such efficiency as to yield a high percentage of recovery of mineral.

Another object of the invention is to provide a vibrator of the type mentioned having means for adjusting it to vary the characteristics of the strokes imparted to the concentrating table according to differing kinds or conditions of the ores or other materials to be separated, and thereby attain a high recovery of minerals or other valuable constituents.

Another object is to provide a vibrator of novel construction for imparting to a concentrating table differential strokes for effecting the separation of coarse particles of minerals or other constituents from ore or other material.

A further object of the invention is to provide a novel vibrator which is capable of being adjusted and operated to effect high efficiency recovery of fine particles of the valuable constituents from ore slimes, or coarse particles from ore sands or other material.

A further object of the invention is to provide, in a vibrator as mentioned, means whereby both

2

the length of the strokes and the characteristics of the same may be readily and minutely adjusted to suit the various conditions and qualities of the material to be operated upon in order to recover a high percentage of the mineral therefrom.

A further object of the invention is to provide a novel self aligning and automatic take-up connection between the vibrator mechanism and the separating table.

10. Other objects will appear hereinafter. With these objects in view the invention consists generally in a separating table, and resilient means constantly tending to move the table in one direction, in combination with means for imparting a desired variable retractive movement to the table, and for controlling the movement imparted by the first mentioned means, so as to impart the desired characteristics to the motion of the table in both directions.

15. More specifically the device embodying the present invention comprises a main frame or casing, a vibratory yoke mounted for reciprocation in said casing, a toggle interposed between said casing and said yoke for imparting motion to the latter, a cam face on one link of the toggle, a rotary eccentric member engaging said cam face to actuate said toggle, and a connection between said yoke and a concentrating table for the material to be separated.

20. The outer ends of the toggle levers or links are seated in bearing blocks adjustably mounted on the frame and yoke respectively. The aforesaid cam is on the link which is seated upon the frame, and the seat is so positioned that any adjustment thereof will vary the relative position of the cam with relation to the rotary actuating member, thereby varying the characteristics of the motion imparted to the yoke and table.

25. The bearing block on the yoke is arranged for adjustment in a path at an angle to the perpendicular, and adjustment of said block varies the length of the stroke or movement of the yoke and table.

These two adjustments are each practically infinite within limits, so that infinite and minute variations may be made, both in the length of the stroke or movement of the table, and also the characteristics of the stroke, according to the type and quality of the material being treated, in order to obtain the most efficient separation.

30. The proper characteristics of the motion imparted to the table is desirable at all times, but is frequently of vital importance when treating slimes containing certain minerals in minute particles or of close specific gravities; a very slight

change in the characteristics of the motion often changing an unprofitable, low percentage recovery into a high percentage and profitable one.

The invention further consists in other novel features and combinations and arrangements of parts, as will be fully described hereinafter and particularly pointed out in the claims.

The invention will be more readily understood by reference to the accompanying drawings forming a part of this specification and in which:

Fig. 1 is a plan view of the vibrator with the cover plate removed,

Fig. 2 is a longitudinal section on the line 2—2 of Fig. 1,

Fig. 3 is a transverse sectional view on the line 3—3 of Fig. 2, illustrated upon an enlarged scale,

Fig. 4 is a similar view taken on the line 4—4 of Fig. 2,

Fig. 5 is a detail section taken on the line 5—5 of Fig. 2, also upon an enlarged scale,

Figs. 6 to 9 inclusive are diagrammatic views illustrating various adjustments of the toggle seats with resultant movements imparted to the yoke,

Fig. 10 is a diagram illustrating the characteristics of the motion imparted to the yoke and table, and

Fig. 11 is a plot illustrating the variations in the characteristics imparted to the motion due to adjustment of the cam seat.

Fig. 12 is a view similar to Fig. 5, but with parts omitted to show the shape of the bearing in the bearing block.

Referring to the drawings, 21 indicates the main frame or casing of the device. This comprises a bottom 22, sides 23, and ends 24 and 25 respectively. The bottom of the casing is formed with a central, longitudinally disposed sump or well 26 which is spanned, intermediate its ends by a bar 27 in the plane of the bottom 22. The end 25, of the vibrator casing, which is adjacent the concentrating table will be designated as the rear end, and the opposite end 24 as the forward end. At the rear end of the well 26 is an upwardly and rearwardly inclined guideway 28 for a bearing block 29, which will be more fully described hereinafter. The guideway 28 extends downwardly to a stop flange 30 on the rear wall of the well, and upwardly to an upper stop flange 31 considerably above the bottom of 22 of the casing.

Slidably mounted on the bottom 22, between longitudinally disposed lateral guides 33, preferably integral with the casing, is a yoke 34. This comprises a pair of longitudinally disposed side bars 35, an upwardly arched transverse member 36 connecting the rear ends of said bars, and a connecting member 37 adjacent the forward ends of the bars. The member 37 is formed to include a guide 38 similar to the guide 28 which forms an integral part of the casing as above described, but inclined upwardly and forwardly. The lower portion of the guide member 37 extends downwardly into the well or sump 26 and is provided at the lower end with a stop flange 39 for a sliding block 40, and at the upper end is formed with a stop flange 41.

The arched rear member 36 of the yoke is provided with a threaded bore 42 to receive the threaded end 43 of a draw bar 44, which draw bar is connected in a manner hereinafter described, to a concentrating table 45. Above the bore 42, the arch member is split, as at 46 forming jaws 47, and a bolt 48 extending through said jaws 75

clamps the draw bar securely in adjusted position.

To move the table in one direction, that is rearwardly in the form illustrated, a pair of helical springs 49 are provided, one upon each side of the yoke 34, and said springs are interposed between abutments 50 on the yoke and a spring compression plate 51 located in the forward end of the casing 21. A spring compression screw 52 is threaded centrally through the plate 51 and impinges against the wall 24. Spring guides 53 are provided within the springs. These each comprise a bar, cruciform in cross section for the major portion of its length, and having cylindrical head 54 terminating in a rounded or semi-spherical end 55. The forward ends 56 of the guides are reduced in diameter and are seated in holes provided for them in the adjacent ends of the plate 51. Guide pins 57 hold the ends 56 of the bars securely in the compression plate and extend upwardly above the plate to engage the edges of longitudinally disposed guide flanges 58 on the inner faces of the side walls of the casing, to properly center the plate 51 and said flanges engage the top of the plate 51 and thereby prevent it from rising and thus throwing the springs out of alignment with the yoke. It should be noted that this construction also constitutes an equalizer for the springs, so that uniform pressure is constantly applied to both sides of the reciprocating yoke.

Interposed between the bearing block 29 supported in the main frame or casing 21 and the bearing block 40 mounted on the vibratory yoke 34, is a toggle consisting of a cam lever 59, and an associated lever or link 60 hingedly connected therewith by a knuckle joint 61.

The cam lever 59 is of integral construction and comprises a pair of parallel arms 62—62 having semi-cylindrical journals 63 at one end and cam faces 64 on their upper edges at the opposite ends from the journals. A transverse member 65 connects the cam ends of the arms below the level of the cam faces, and a transverse member 66, substantially flush with the upper edges of the arms, spans the space between them adjacent the journal end. Extending between the journals 63 and concentric therewith is a cylindrical element 67. The member 65 is provided with a bearing 68 forming a part of the knuckle joint 61. The link 60 is preferably a straight flat bar provided at its ends with semi-cylindrical journals 69 and 70, respectively.

The journals 63 of the cam lever are seated in bearings 71 in the adjustable block 29, and the journal 70 of the link 60 is seated in like bearings in the block 40.

A U-shaped leaf spring 73, having a short arm 74 and a long arm 75, is arranged with the bent portion extending around the cylindrical element 67 of the cam lever, and with the short arm 74 bearing against a flange or rib 76 on the under face of the transverse member 66 and is bent upwardly to engage the forward edge thereof and thereby maintain the intermediate portion of the spring in close engagement with the cylindrical element 67. The longer arm 75 of the spring is bent downwardly adjacent its end, and curved as at 77 to engage and ride upon the upper face of the bar 27 of the casing. The spring 73 is quick loading and it tends to constantly force the knuckle 61 upwardly, it being heavily loaded when the toggle members are in nearly a straight line and tending to break the toggle at which time the springs 49 act with their least effectiveness to

break the toggle. By this construction and arrangement of the spring, no variation in the compression thereof will occur when the bearing block is raised or lowered for adjustment as will be described hereinafter.

Mounted in bearings 78 on the sides 23 of the casing, is a shaft 79, having a crank or eccentric journal 80 positioned above the cam faces 64, and carrying a roller 81 which includes a pair of spaced cylindrical portions 82—82 with which the cam faces 64—64 are constantly held in engagement by the leaf spring 73, or by the coil springs 49.

The roller 81 is divided longitudinally into two similar halves bolted together in place to facilitate assemblage on the eccentric portion of the shaft. Each of said halves includes half of each of the cam engaging portions 82—82 connected at their ends by bars 83, and intermediate the ends by bars 84, the inner surfaces of said bars 83 and 84 constituting portions of the bearings of the roller on the eccentric. Bolts 85 extend through the bars 83 to secure the roller sections together. The bars 83 and 84 being spaced apart affords means whereby lubricant may readily reach the bearings.

When the mechanism is in a stable position of rest the center of the eccentric 80, and hence of the roller 81, is on the side of the axis of the shaft diametrically opposite the point of contact of the roller with the cam. This point of contact when the cam lever bearing is at the highest point of adjustment, as will be described hereinafter, is indicated at 86. In this position the toggle is raised or flexed to its greatest height by the pressure of the springs 73 and 49.

From this position any rotation of the shaft will depress or straighten the toggle and move the yoke 34 and table 45 against the pressure of the springs until the center of the eccentric 80 and roller 81 lies directly between the axis of the shaft and the point of contact of the roller with the cam. Further rotation again permits the springs 49 to move the yoke in reverse direction; but this movement is controlled by the engagement of the cam 64 with the roller 81.

It is therefore obvious that the characteristics of the movements of the yoke and table are determined by the character or shape of the cam 64, together with the initial position of the cam with relation to the shaft 79 and to the plane of movement of the yoke. In the wet treatment of finely pulverized ores, and particularly those of a complex nature, the characteristics of these movements are vital to the highest efficiency of the device.

Such motions as are found desirable may be attained in a construction above described, by means of the improved cam forming a part of this invention, and the means hereinafter described for adjusting the same.

As shown in the drawings the cam face 64 curves upwardly as at 87 from substantially the contact point 86 and toward the pivoted end of the cam lever, and extends straight as at 88 in the opposite direction in a plane tangential to the curve of the portion 87. Preferably, the plane of the straight portion 88 lies parallel to a plane intersecting the center of the roller 81 and the pivotal axis of the cam lever 59 while said roller is in contact with said straight portion, and the curved portion 87 is struck as a center from a point in a line intersecting the centers of the shaft 79 and said roller and the point of contact of said roller with said straight portion while the latter is closest to the center of said shaft, and 75

has a radius equal to the diameter of the roller, but the radius of this curved portion 87 may be made greater or less than the diameter of the roller 81, according to the maximum sharpness of motion desired at an end of the stroke.

In Fig. 10 of the drawings a diagrammatic showing is made of the movement of the yoke when the cam lever 59 is at a high point of adjustment; and in Fig. 11 this movement is plotted, as well as a similar movement when the cam lever bearing block 29 is at a lower point of adjustment, so as to graphically show the differences in the characteristics of the motion attained by simply adjusting the pivot point of the lever and consequently the initial position of the lever with relation to the eccentric and to the plane of movement of the yoke.

As shown in Fig. 10, the circle 89 indicates the throw of the eccentric. This is divided into twelve equally positioned stations indicated by the letters *a. b. c. d.*, etc., the station *a* being shown initially as diametrically opposite to the contact point 86 of the cam and roller. With each of said stations as a center, and assuming the rotation to be in the direction of the arrow *X*, dotted circles are delineated showing the position of the roller when its center is at each station, together with the corresponding positions of the levers 59 and 60 for each downward stage. The positions of the levers at the several stations on their upward movement is omitted to avoid confusion; but all of the resultant positions are indicated at the lower right corner of Fig. 10, where the horizontal line *Z* indicates the plane of the movement of the bearing 70. The vertical lines extending above the line *Z* indicate the stages on the downward movement of the cam, and those extending downwardly, the position on the upward movement thereof.

All of these positions are plotted in Fig. 11, the arrow heads in said figure indicating the direction of movement of the bearing, and therefore of the yoke and concentrating table. The dotted curved line in this figure depicts the movement when the block 29 is adjusted to a lower position than that shown in Fig. 10.

It will be apparent that as the pivot 63 of the cam lever is lowered the angle of the straight portion 88 of the cam to horizontal will be increased and that the point of contact of the roller 81 therewith, when in the stable position of rest as above described, is shifted toward the end or toe of the lever and further from the curved portion 87 of the cam, so that a greater portion of the movement of the yoke and table is controlled by the straight portion of the cam and less by the curved portion. This shift will be apparent by comparing Figs. 6 and 7.

In separating the fine particles of mineral from the slime, the jar incident to a too sudden change from the retractive movement to the opposite movement of the table, or a too rapid movement toward the discharge position will tend to vibrate the settled particles back into suspension in the water or carrying medium; whereas a gentle change in the reversal of movement will permit the particles to settle on the deck of the table, and a sudden reversal at the discharge end of the stroke will then draw the table from beneath the settled particles and produce a proper and high percentage discharge of the valuable constituents.

The opposite is the case with coarser materials, or sands, as the coarser and heavier particles will not be so readily driven back into suspension. Therefore in treating such materials a reversal of

the direction of rotation of the eccentric, as indicated by the arrow Y in Fig. 10, is desirable.

In treating mixed feeds of fine and coarse particles, and unclassified or complex ores, the separation can in most cases, be readily made by proper adjustments of the toggle seats together with selection of the proper direction of rotation of the eccentric.

The variations in the characteristics of the stroke as above described is had by an adjustment, up or down, of the bearing block 29; but it is frequently desirable to change the length of the stroke, which is done by raising or lowering the bearing block 40 on the yoke. In Figs. 6 to 9 inclusive various adjustments of both bearing blocks are shown, illustrating the resultant changes in the length of the strokes.

The means provided for adjusting the bearing blocks is as follows: The guideway 28 formed in the casing 21 includes a preferably cylindrical bearing face 90 extending between the stops 30 and 31, and the guideway 38 on the yoke is similarly formed, having a cylindrical bearing face 92; these cylindrical bearing faces rendering the toggle bearings self-aligning.

The adjustable bearing blocks 29 and 40 are identical in form and interchangeable; and are symmetrically formed above and below a transverse central plane so that in assembling the device either end may be placed uppermost. This is a material consideration in the cost of manufacture, assembling and maintenance.

Each of said blocks comprises a body portion having a cylindrical rear face 91 fitting the cylindrical face of the guides, and provided in its front face with the transverse semi-cylindrical bearing 71 for the journals 63 and 70 of the toggle levers. Forwardly of the bearings 71, the face of the block is leveled or flared as at 93 to avoid interference with the swing of the toggle members, and to act as guides in assembly, and to also prevent the outer ends of the toggle members from displacement from the bearing blocks in the event of spring failure.

The bearing blocks 29 and 40 are adjustable in their respective guides by screws 94 swiveled in the upper flanges 31 and 41 and threaded through the blocks respectively. These screws are provided at their upper ends with hand-wheels or grips 95, the hubs of which bear upon washers 96 interposed between the same and the flanges 31 or 40. A collar 97 is fixed to each screw beneath the upper flange of the guides to prevent upward longitudinal movement of the screw and to limit maximum upward adjustment of the blocks.

Since the guideways 28 and 38 converge from opposite sides toward a plane transverse to the direction of reciprocation of the yoke 34 and intersecting the center of the intermediate pivotal joint 61 connecting the toggle links, adjustment of the bearing block 29 along its guideway will change the angular relation of the cam surface 65 with the eccentric and thereby effect adjustment of the characteristics of the strokes imparted by the toggle to the yoke without appreciable alteration of the length of the strokes thereof because the position of the toggle link 60 with relation to the eccentric will not be appreciably changed by such adjustment, and adjustment of the bearing block 40 along its guideway will effect adjustment of the length of the strokes imparted by the toggle to the yoke without appreciable alteration of the characteristics of the strokes of the yoke because the toggle-

link 60 will merely swing during such adjustment about the intermediate pivotal joint 61 and shift the yoke according to the extent of adjustment of the bearing block 40.

The toggle member 59 is provided with a tapered hole 59a which, during operation of the vibrator, will be submerged in a bath of oil contained in the casing, and will cause oil to spurt upwardly therethrough onto the roller to lubricate it and adjacent parts at each downward thrust of said toggle member.

The casing 21 is provided with a cover plate 101 which rests upon the upper edges of the sides and ends of the casing and is provided with a groove 102 in its underface to receive said edges. The cover plate is arched as at 103 to span the shaft 79, eccentric 80, and roller 81; and is provided with openings 104 and 105 located above the hand wheels 95 to give access to the same. Auxiliary covers 106 and 107, which are preferably hinged to the cover plate 101, are provided for the openings 104 and 105. The openings 104 and 105 permit ready access to the hand-grips 95, so that the device may be readily adjusted while in operation, to secure the best results with the material being treated.

With the above described mechanism, it is obvious that an almost infinite number of minute variations may be made in both the length of the movement of the yoke 34, and also in the characteristics of the movement irrespective of the length thereof; but to be completely effective, this motion must be transmitted to the table 45 without variation and without lost motion. To this end a novel self-aligning and automatic take-up connection is provided between the draw bar 44 and the table.

The projecting end of the draw bar 44 is formed with a cupped head 108 having substantially parallel inner and outer end walls 109 and 110. The outer wall is provided on its inner face with a spherical socket 111 in which is seated the spherical portion 112 of the head 113 of a link 114. The inner end of the head 113 is conical as indicated at 115, and terminates in a spherical apex 115a whose center is common with that of the spherical portion 112 and bears against a wedge block 116 interposed between the same and a downwardly inclined face 117 of the wall 109.

The opposite end of the link 114 is provided with a globose head 118 having a hemi-spherical end 119. A bore 120 extends transversely through said head to receive a pin 121, the projecting ends of which engage in brackets 122 on the adjacent end of the table 45. Said brackets 122 have tapered openings 123 at the apices of which are bearings 124 for the pin 121. The bore 120 is of greater diameter at the center of the head 118 than that of the pin, and flares outwardly on the side adjacent the table, as at 125, forming a pivot edge 126 which bears against the pin, and from which edge as a center the radius of the hemi-spherical end 119 is struck. A downwardly tapered block 127 is interposed between a downwardly inclined surface 128 on the table 45 and the end of the head 118; the taper of the block being the same as the inclination of said face so that the surface engaging the head 118 is vertical. Said vertical surface is provided with a longitudinally disposed groove 129 of the same cross sectional curvature as that of the end of the head, the center of said curvature being at the edge 126 above described, so that the link 114 has ample pivotal movement to avoid any

binding or straining between the link and the table. This also applies to the pivotal connection of the link with the draw bar head 108.

It is also obvious that any wear of the parts will be constantly taken up by the tapered elements 116 and 127, these elements adjusting themselves under the influence of gravity, and the angle of taper being sufficiently small to overcome forces tending to squeeze them out of position. Consequently, both the length of the stroke imparted to the yoke 34, and the characteristics of said stroke will be communicated to the table without any variation whatever.

A fly-wheel 130 is clamped or otherwise fixed on the shaft 79 to provide uniformity of speed of rotation thereof during each revolution, and to cause the vibrator to operate smoothly, and the vibrator may be driven conveniently from an electric motor or other source of power which may be belted to the fly-wheel.

We claim:

1. In a device of the class described, a support, a yoke mounted for reciprocation on said support, a toggle interposed between said support and said yoke, a cam surface on one link of said toggle, a rotary eccentric engaging said cam surface, said cam surface comprising a curved portion extending in one direction from approximately the point of contact of said eccentric with the cam when the center of rotation of the eccentric is closest to the cam, and a flat surface tangential to said curved portion and extending in the opposite direction from said point of contact, and means for connecting said yoke to a concentrating table.

2. In a device of the class described, a support, a reciprocatory member on said support, a toggle interposed between said support and said member, a cam face on one element of said toggle, a rotary eccentric engaging said cam, said cam comprising a straight portion on one side of said eccentric and a curved portion on the other side of said eccentric, and means for adjusting the cam bearing toggle element to vary the angular position of the straight portion of the cam with relation to the eccentric.

3. In a device of the class described, a support, a reciprocatory member on said support, a toggle comprising a pair of links, a cam on one of said links, a journal on the cam bearing link, a seat on said support for said journal, a seat on the reciprocatory member for the other link, a rotary eccentric engaging said cam, said cam having a straight portion lying substantially in a plane parallel with a plane common to the center of said eccentric and the axis of said journal while the eccentric engages said straight portion, and a curved portion tangent to said straight portion.

4. In a device of the class described, a support, a reciprocatory member on said support, a toggle comprising a pair of links, a cam on one of said links, a journal on the cam bearing link, a seat on said support for said journal, a seat on the reciprocatory member for the other link, a rotary eccentric engaging said cam, said cam having a straight portion in a plane parallel with a plane common to the center of said eccentric and the axis of said journal, and a curved portion tangent to said straight portion and having a radius substantially equal to the diameter of the eccentric.

5. In a separator head motor, a rotary eccentric in combination with a lever having a pivotal mounting at one end and a cam on the other end

actuated by said eccentric, said cam having a straight outer end portion in a plane parallel with a plane common to the center of said eccentric and the axis of said pivotal mounting, and a curved portion tangential to said straight portion and struck as a center from a point substantially in a line intersecting the center of the eccentric and its axis of rotation and the point of contact of the eccentric with said straight portion while the latter is closest to the axis of rotation of the eccentric.

6. In a device of the class described, a support, an eccentric mounted on said support and adapted to be rotated in either direction, an angularly positioned guideway on said support, a bearing member adjustably mounted on said guideway, a reciprocatable member on said support, a toggle interposed between said bearing member and said reciprocatable member, and a cam on the toggle element engaging said bearing member, said cam comprising a straight outer portion and curved inner portion tangent to said straight portion, and means for connecting a separating table to said reciprocatable member.

7. In a device of the class described, a support, an eccentric rotatably mounted on said support, a reciprocatory member on said support; an inclined guideway on said support, a bearing block adjustably mounted on said guideway, a toggle comprising a link having one end journaled in said bearing block and an associated link having bearings on said reciprocatory member, a cam on the first said link and a spring for maintaining said cam in engagement with said eccentric, said spring being U-shaped with its bent portion arranged about the journaled end of the cam lever and the free ends engaging under said lever and on said support, respectively, whereby adjustment of said bearing block will not vary the loading of said spring.

8. A vibrator for imparting differential reciprocatory motion to a surface for advancing material thereover, comprising a support, a toggle embodying pivotally connected members one of which has a bearing on the support and the other having means for imparting motion to said surface, an eccentric, and a cam on one of the toggle members having a curved portion extending in one direction from the point of contact of the eccentric with the cam when the center of rotation of the eccentric is closest to the cam, and having a straight portion tangential to said curved portion at said point of contact and extending in the opposite direction therefrom.

9. A vibrator as defined in claim 8, including means for varying the angular position of said cam relatively to said eccentric.

10. A vibrator comprising a support, a shaft mounted rotatably therein and provided with an eccentric, a cam lever pivotally mounted in the support and having a cam surface thereon engaging the eccentric, said cam surface having a curved portion extending in one direction from the point of contact of the eccentric with the cam when the center of rotation of the eccentric is closest to the cam, and having a straight portion tangential to said curved portion at said point of contact and extending in the opposite direction therefrom, and means for transmitting vibratory motion from said cam lever to the structure to be vibrated.

11. A vibrator as defined in claim 10, including means for adjusting the angular relation between said cam lever and eccentric in the plane of rotation of the eccentric.

12. A vibrator comprising, in combination, a support, a reciprocatory member mounted on the support and having means for connecting it to a structure to be vibrated, a rotatable eccentric mounted on the support, a toggle comprising a pair of links having a pivotal connection between them at a point intermediately of the length of the toggle, one of said links having a cam surface thereon engaged by the eccentric, bearings pivotally engaged by the remote ends of the toggle links, and guides on the support and reciprocatory member respectively along which the respective bearings are independently adjustable, said guides converging from opposite sides toward a plane transverse to the direction of reciprocation of said member and intersecting the center of the intermediate pivotal connection between the toggle links.

FANNIE B. JAMES,
Executrix of the Estate of Ulysses S. James, 20
Deceased.
